STRIPPING CATHODE

Whitman Symmes, Kellogg, Idaho

Application August 25, 1947, Serial No. 770,502

3 Claims. (CL. 204—281)

1

The object of my invention is to provide a stripping cathode from which the deposited sheet of metal may be stripped by mechanical means. The present practice in electrolytic zinc refineries is to separate the deposited sheet of metal by means of a chisel in the hand of an operator who drives it between an edge of the deposited sheet of metal and the permanent cathode plate. This often requires several blows of the chisel.

Advantages of my invention are that the edge of the deposited sheet of metal can be separated from the permanent cathode plate for a definite distance, without fail, and without injury to the cathode plate or the insulating member which I employ thereon. Under these conditions the cathode can be stripped in a suitable machine, instead of by hand.

Figure 1 is a view in side elevation of an unplated cathode embodying my invention;

Figure 2 is a view in side elevation of a slightly different form of unplated cathode;

Figure 3 is an enlarged view in side elevation of the insulating member employed in the cathode shown in Figure 1;

Figure 4 is a sectional view taken on the line 4—4 of Figure 3, showing the insulating member attached to the cathode and the metal plated on the cathode;

Figure 5 is a view like Figure 4, showing the metal being pushed away from the cathode;

Figure 6 is a view, on an enlarged scale, of the upper right corner of the cathode and insulating member of Figure 2;

Figure 7 is a section view on the line 7—7 of Figure 6; and

Figure 8 is a fragmentary sectional view on the line 8—8 of Figure 6.

In the illustrations the same numbers indicate the same parts throughout. Figure 1 is a side elevation of an unplated cathode which has insulating members and passageways within the periphery of the cathode plate. The cathode bar 1 is integral with the cathode plate 2, and the surface of the electrolyte in which it is immersed is indicated by the broken line A—B. An insulating member on the front side is shown at 3, and a passageway through the cathode is shown at 4. Another passageway through the cathode is shown at 5, and a similar insulating member on the opposite side of the cathode plate is indicated by broken lines at 6.

Figure 2 shows another form of an unplated cathode which has insulating members and passageways at the outer edges of the cathode plate. The cathode bar 7 is integral with the cathode

2

plate 8, which has on its front side an insulating member 9. The cathode plate 8 has an indentation 10 which serves as a passageway connecting the opposite sides of the cathode by means of the space around its edge. A similar insulating member on the opposite side of the cathode plate is indicated by broken lines at 11, adjoining the indentation 12. The level of the electrolyte is indicated by the broken line C—D.

Figure 3 shows, on a larger scale, the construction of the insulating member 3. The passageway through the cathode is shown at 4, and 13 and 14 are bolts above the surface of the electrolyte A—B, for securing the insulating member to the cathode plate.

Figure 4 illustrates the appearance of a cathode along the broken line 4—4 shown in Figure 3, after the permanent cathode plate 2 has had a sheet of metal 15 deposited on it in the electrolyte. Note that the cathode plate 2 is bevelled at the passageway 4 and that the insulating material of the member 3 is extended substantially through the passageway so that the metal deposit cannot enter the passageway.

Figure 5 illustrates the manner in which the deposited sheet of metal is separated from the permanent cathode plate at the beginning of the stripping operation. The tool employed to press off the deposited sheet of metal is indicated in outline at 16.

Figure 6 is an enlarged elevation of insulating member 9 shown in Figure 2. Bolts attaching it to the permanent cathode plate are shown at 17 and 18. An extension of the cathode plate 8 beyond the insulating member 9 is shown in this figure. In present practice, in some plants, the cathode plates are dropped into wooden slits that are inserted inside the tanks containing the electrolyte solution and their edges are thereby protected against depositions of metal. In such cases it is necessary to set the insulating member 9 a sufficient distance back from the edge of the cathode so that it will not strike the wooden strips. Figure 6 differs from Figure 2 in this respect. In some plants the cathode plates hang freely in the electrolyte solution. In such cases it is not necessary to set the insulating member back.

Figure 8 illustrates the manner of removing the deposited sheet of metal 19, by a tool which is shown in outline at 20.

The insulating member may be made of glass, porcelain, plastic or other suitable material, its contacting edges being made to exactly fit the cathode plate. The thickness of the metal of

3

the cathode plate may be reduced from either side by a beveled or curved surface. In Figures 4 and 5 the edge 21 of the cathode plate is bevelled and the insulating member 3 has a lip 22 that overlaps and covers the bevelled edge 21 so that the deposited metal is prevented from attaching itself to the bevelled edge of the cathode. In Figure 8 the cathode face opposite the insulating member 9 is curved at 23 to meet the outer edge of the member 9, thus keeping the metal deposit from building up on an edge of the cathode. In both forms (Fig. 5 and Fig. 8) the exterior angle between the adjacent deposit surface and insulating surface exceeds 180 degrees and in fact closely approaches 270°. A thin or sloping edge of the plate should be employed at its contact with the insulation, in order that a minimum of pressure may be employed to separate the deposited sheet of metal. The insulating member may be used as a guide to spot the instrument that is employed to separate the deposited sheet of metal. The insulating member may be attached to the cathode plate by rubber cement, and further secured by bolts as illustrated. In the electrolyte the deposited metal will build itself out from the edge of the conducting surface into the passageway sufficiently so that the sheet of deposited metal may be loosened by pressure against it from the opposite side. In zinc practice a one-half inch round passageway through the cathode plate will be restricted to about three-eighths inch diameter; or if there is a one inch passageway around the periphery of the cathode, the extension of deposited metal into the passageway will be about one-eighth inch. This deposit of metal into the passageway takes place in the form of knobs and trees, which firmly unite to each other and to the main deposited sheet of metal. A light pressure is sufficient to break the vacuum between the deposited metal and the cathode plate at the edge of the passageway, after which the separation is easily followed up. The two sheets of metal deposited on the opposite sides of the cathode can be stripped simultaneously. Figures 3, 4, and 5 show the preferred form.

I claim:

1. A stripping cathode plate having an exposed conductive surface on one of the two sides thereof where metal is to be electrolytically deposited, said plate having an aperture therein, the edge face of the plate defining the aperture being tapered from the conductive surface toward the

4

other side of the plate whereby the area of the aperture increases toward the said other side, an insulating member fixed to said plate on the side opposite said conductive surface and having an aperture coinciding with the aperture in the plate, the insulating member covering said tapered edge face and extending to said conductive surface.

2. A stripping cathode plate having an exposed conductive deposit surface on one of two sides thereof where metal is to be electrolytically deposited, a hard durable insulating member covering a portion of the other side of said plate, said insulating member having an exposed edge face extending transversely to the plane of said plate and meeting the said exposed conductive deposit surface at an angle greater than 180 degrees, so that stripping force applied parallel to the edge face of said insulating member against deposited metal overhanging said edge face is directed away from said deposit surface.

3. A stripping cathode plate having an exposed conductive deposit surface on one of two sides thereof where metal is to be electrolytically deposited, a hard durable insulating member covering a portion of the other side of said plate, said insulating member having an exposed edge face extending transversely to the plane of said plate and meeting the said exposed conductive deposit surface at an angle greater than 180 degrees, so that stripping force applied parallel to the edge face of said insulating member against deposited metal overhanging said edge face is directed away from said deposit surface, the said plate being bevelled to reduce the thickness thereof adjacent said exposed edge face.
